COUPLING DEVICE FOR HIGH-FREQUENCY APPARATUS

John S. Donal, Jr., and Howard R. Hegbar, Princeton, N. J., assignors to Radio Corporation of America, a corporation of Delaware

Application July 29, 1943, Serial No. 496,570

12 Claims. (Cl. 178—44)

1

Our invention relates to coupling means for ultra high frequency electronic apparatus and more particularly to coupling means useful in coupling evacuated envelopes such as electron discharge devices utilizing cavity resonators, wave guides, coaxial lines and other like circuit elements with each other, or as a radiator for an evacuated cavity resonator or the like.

Coupling means for coupling evacuated hollow conducting elements, such as cavity resonators utilized with electron discharge devices, with other cavity resonators, wave guides and coaxial lines, do not lend themselves readily to machine made mass production. The assembly of transmitting or receiving type tubes using cavity resonators or metal envelopes presents considerable difficulties since in the usual coupling device, such as the coaxial line, the central conductor must be installed in a late stage of the assembly. The central conductor must be sealed through the metal envelope of the tube or the resonator to maintain the vacuum within the electron discharge device. This requires careful sealing and may bar the use of material for the conductor having the optimum characteristics for high frequency conductivity. If it is desired to make the outer conductor of the coaxial line of material having poor radio frequency conductivity, it is common to silver-plate or otherwise treat the inner surface of the outer tubular conductor to increase its radio frequency conductivity. With the central conductor sealed-in this becomes a difficult process. Where high voltages are utilized corona losses occur at the tip of the inner conductor when this inner conductor is utilized as a radiator or as a coupling rod within a second resonator, waveguide or coaxial line, since the corona takes place where the electrical field is the most intense, which is at the tip of the inner conductor. Means must also be provided for mechanically securing the coupling device to the resonator or waveguide into which the high frequency energy is to be fed. Reflection at the juncture of the coupling device such as the juncture of the coaxial line and the waveguide or resonator coupled to the coaxial line must be prevented. Extending the coaxial line directly within the waveguide does not provide a juncture at which the impedance of the coaxial line and the impedance of the waveguide or resonator are matched, thus causing reflection. The problem is made more pressing when it is desired to bias the coaxial line and the waveguide or resonator coupled thereto at different voltages since this requires spacing between the waveguide and co-

axial line or resonator and provides another cause or source of radio frequency losses through the space between the coupled elements.

It is, therefore, an object of our invention to provide an improved coupling device for coupling evacuated hollow conducting members to a waveguide or cavity resonator.

It is another object of our invention to provide such a device which facilitates machine-made mass production.

A further object of our invention is to provide such a device which will greatly facilitate the manufacture and assembly of transmitting and receiving tubes utilizing cavity resonators or metal envelopes.

A still further object of our invention is to eliminate the seals between the central conductor and the outer conductor of a coaxial line used as a coupling device, as has been required in the past.

20 A further object of our invention is to provide such a device in which treatment of the inner surfaces of the outer conductor of the coaxial line for improving its radio frequency characteristics is facilitated.

25 Another object of our invention is to provide such a coaxial line coupling device in which the corona losses from the inner conductor are minimized.

30 A still further object of our invention is to provide such a coupling device which provides an easy and exact electrical connection and which may be rigidly connected to the waveguide or resonator.

Another object of our invention is to provide 35 mechanical protection to minimize breakage of the glass parts of the envelope and coupling device.

The novel features which we believe to be characteristic of our invention are set forth with particularity in the appended claims, but the invention itself will best be understood by reference to the following description taken in connection with the accompanying drawing in which Figure 1 is a coupling device made according to our invention 40 associated with an electron discharge device having a metal envelope and a waveguide and shown partially in section; Figure 2 is an enlarged view showing details of the construction of the termination of the coaxial line coupling device shown in Figure 1; and Figure 3 is a modification of the device shown in Figure 2 for permitting direct voltage differentials between different portions of the apparatus used in our invention.

45 In Figure 1 a coupling device made according to our invention is used to couple a magnetron

within an evacuated envelope to a waveguide. The magnetron includes the evacuated metallic envelope 10 having exhaust tube 11 and containing the magnetron anode block 12 provided with a plurality of radially directed anode segment elements 13, the space between each of the elements 13 providing in effect a cavity resonator. Positioned axially of the magnetron is an indirectly heated cathode 14 provided with leads 15 and 16 extending through the shield 17 terminated by insulating cup member 18 through which the leads are sealed. The means for applying a magnetic field are not shown, but provide a field parallel to the cathode and between the cathode and the anode segments.

In accordance with our invention we provide a coupling device comprising a coaxial line having an outer hollow conductor 20 closed at one end by means of the cone-shaped insulating cap member 21. The outer conductor 20 is sealed to the envelope 10 and extends within an opening provided for it in the magnetron anode 12. An inner conductor 22 is positioned coaxially of the outer conductor 20 and abuts the inner wall of the cone-shaped insulating cap 21 near the tip but is not sealed thereto. The other end of the inner conductor 22 is provided with coupling loop 23, one end of which is connected to the ring member 23'. We provide a cup-shaped member 24 having lip or flange 24' which rigidly supports the coaxial coupling line on the waveguide 25 having an opening 26 through which the inner coaxial member extends, the inner end of the coaxial member extending at least one-quarter wavelength beyond the outer conductor 20 and within the waveguide 25 to generate an electromagnetic field in response to excitation of the coaxial line by the magnetron.

In order to provide an exact electrical connection between the waveguide and the coupling member, the cup-shaped member 24 is spaced from the outer conductor 20 for a distance equal to a half wavelength of the generated radio frequency voltages. This in effect provides a zero impedance between the inner end of the cup-shaped member adjacent the aperture and the outer conductor 20 so that in effect the result is as if the end of the outer conductor were connected directly to the waveguide 25 so far as electrical conditions are concerned. The lip 24' may be directly connected to the outer surface of the waveguide 25.

This form of device permits the coupling of an evacuated container which may be a cavity resonator or an electron discharge device such as described. A device made according to our invention is readily produced by a mass process since all parts may be made exactly to measure prior to assembly. Because of the independence of the inner and outer conductors, and because no sealing is required between the inner and outer conductors, the coupling device may be quickly assembled. Seals between the inner and outer conductors are eliminated, thus reducing the likelihood of leaks and simplifying construction. Because the inner conductor may be easily removed, treatment of the inner surface of the outer conductor for improving the radio frequency impedance is great facilitated. Because of the construction of the insulating cap and because the inner conductor does not extend through the cap the corona losses from the inner conductor are minimized, since corona must take place from the surface of the glass where the electrical field is less than at the surface of the conductor which

has a smaller radius of curvature than does the glass sheath. Because of the formation of the supporting cup 24, the impedance between waveguide and coupling member may be reduced to a minimum while at the same time it serves to protect the seal of the cap 21 to the outer conductor 20.

Figure 2 is an enlarged view of the construction of the end of the coupling line and its method of support in the waveguide 25. The dimension *a* of Figure 1 is of importance whereas that of *b*, the lip, is not critical in the arrangement shown in Figures 1 and 2. As pointed out above dimension *a* is equal to a half wavelength of the generated radio frequency voltages.

Should it be desirable to maintain the waveguide and the tube envelope at two different potentials, our invention may assume the form shown in Figure 3. Positioned between the lip or flange 24' of the cup-shaped member 24 and the waveguide is the insulating washer 27, which may be of mica. In this arrangement the dimension *b* becomes critical since only capacity coupling exists between cup 24 and the waveguide 25, and in order to prevent radiation through this space it is necessary to make dimension *b* effectively equal to a quarter wavelength, taking into consideration the kind of insulation used. Dimension *a* is again one-half wavelength. This in effect is comparable to a quarter wave open transmission line so that the impedance between lip 24' and the waveguide at its inner edge will be zero or substantially zero so that in effect this part of the cap is short circuited to the waveguide.

While we have indicated the preferred embodiments of our invention of which we are now aware and have also indicated only one specific application for which our invention may be employed, it will be apparent that our invention is by no means limited to the exact forms illustrated or the use indicated, but that many variations may be made in the particular structure used and the purpose for which it is employed without departing from the scope of our invention as set forth in the appended claims.

What we claim as new is:

1. A coupling means for ultra high frequency evacuated devices including a coaxial line having an outer tubular conducting member, a cup-shaped element of insulating material sealed to one end of the tubular conducting member and extending outwardly therefrom, and an inner conductor coaxial with said outer tubular conducting member and extending outwardly past the end of said outer tubular conducting member with its end contacting the inner surface of the cup-shaped element, the other end of said inner conductor terminating in a loop electrically connected to the outer tubular conducting member, said inner conductor being supported only at its ends.

2. A first evacuated hollow conducting body resonant at ultra high frequencies, a coupling means for coupling the evacuated hollow conducting body to a second hollow conducting body and including a coaxial line having an outer tubular conducting member, a substantially cone-shaped element of insulating material sealed to one end of the tubular conducting member and extending outwardly therefrom, and a conductor coaxial with said outer tubular conducting member and extending outwardly past the end of said outer tubular conducting member with its end contacting the inner surface of the cone-shaped element at the peak thereof, the

5

open end of the outer tubular conducting member communicating with the first hollow conducting body, the other end of said inner conductor terminating in a loop electrically connected to the outer tubular conducting member.

3. A coupling means for ultra high frequency evacuated devices including a coaxial line having an outer tubular conducting member, a cup-shaped element of insulating material sealed to one end of the tubular conducting member and extending outwardly therefrom and an inner conductor coaxial with said outer tubular conducting member and extending outwardly past the end of said outer tubular conducting member with its end within the cup-shaped element and contacting the inside of said cup-shaped element of insulating material, said inner conductor being supported only at its ends, and a conducting cup-shaped member surrounding the end of said outer tubular conducting member which is sealed to the cup-shaped element of insulating material and spaced from the outer tubular conducting member and connected to said outer tubular conducting member at a point spaced from the sealed end thereof.

4. An evacuated hollow conducting body resonant at ultra high frequencies, a coupling means for said body including a coaxial line having an outer tubular conducting member, a cup-shaped element of insulating material sealed to one end of the outer tubular conducting member and extending outwardly therefrom and an inner conductor coaxial with said outer tubular conducting member and extending outwardly past the end of said outer tubular conducting member with its end within the cup-shaped element, and a conducting cup-shaped member surrounding the end of said outer tubular conducting member which is sealed to the cup-shaped element of insulating material and spaced from the outer tubular conducting member for a length equal to a half wavelength of the operating frequency of the device to which the coupling means is coupled and connected to said outer tubular conducting member, the open end of said coupling means communicating with the interior of the evacuated hollow conducting body, and the open end of said cup-shaped member being adjacent said cup-shaped element of insulating material.

5. A coupling means for ultra high frequency evacuated devices including a coaxial line having an outer tubular conducting member, a cup-shaped element of insulating material sealed to one end of the outer tubular conducting member and extending outwardly therefrom and an inner conductor coaxial with said outer tubular conducting member and extending outwardly past the end of said outer tubular conducting member and its end contacting the inner surface of the cup-shaped element, a conducting cup-shaped member surrounding the end of said outer tubular conducting member which is sealed to the cup-shaped element of insulating material, the walls of said end cup-shaped member being spaced from the outer tubular member and connected to said outer tubular conducting member, a hollow conducting member, having an aperture therein, the end of the coaxial line having the cup-shaped element of insulating material extending within said aperture, a flange on said cup-shaped member fixed to said hollow conducting member, and an insulator between said flange and said hollow conducting member.

6. An evacuated cavity resonator, means for

6

exciting said resonator, and means for coupling said resonator to a radiator and including a coaxial line having an outer tubular member connected to said resonator and communicating with the interior thereof, an insulating cap sealed at the outer end of said hollow tubular member, and an inner conductor coaxial with said outer tubular member and having a loop on one end within said cavity resonator, the other end of said inner conductor extending past the end of the outer tubular member and contacting the inside of said insulating cap, said inner conductor being supported only at its ends.

7. A coupling means for ultra high frequency evacuated devices including a coaxial line having an outer tubular conducting member, a cup-shaped element of insulating material sealed to one end of the outer tubular conducting member and extending outwardly therefrom and an inner conductor coaxial with said outer tubular conducting member and extending outwardly past the end of said outer tubular conducting member with its end within the cup-shaped element, and a conducting cup-shaped member surrounding the end of said outer tubular conducting member which is sealed to the cup-shaped element of insulating material and having its side walls spaced from the outer tubular conducting member and connected to said outer tubular conducting member at a point spaced from the sealed end thereof, the open end of the cup-shaped member being provided with a radially directed flange for securing said coupling means to a hollow conducting body.

8. An evacuated hollow conducting body adapted to be excited at ultra high frequencies, a coupling means for said body including a coaxial line having an outer tubular conducting member, a cup-shaped element of insulating material sealed to one end of the outer tubular conducting member and extending outwardly therefrom and an inner conductor coaxial with said outer tubular conducting member and extending outwardly past the end of said outer tubular conducting member with its end contacting the interior surface of the cup-shaped element, a conducting cup-shaped member surrounding the end of said outer tubular conducting member which is sealed to the cup-shaped element of insulating material and having its side walls spaced from the outer tubular conducting member and connected to said outer tubular conducting member at a point which is spaced from the sealed end thereof, the open end of said coupling means communicating with the interior of the evacuated hollow conducting body, and a second hollow conducting body having an aperture, the end of said coupling means provided with the cup-shaped element of insulating material extending within said second hollow conducting body through said aperture, the open end of said cup-shaped member having a flange securing said coupling means to said second hollow conducting member.

9. An evacuated hollow conducting body adapted to be excited at ultra high frequencies, a coupling means for said body including a coaxial line having an outer tubular conducting member, a cup-shaped element of insulating material sealed to one end of the outer tubular conducting member and extending outwardly therefrom and an inner conductor coaxial with said outer tubular conducting member and extending outwardly past the end of said outer tubular con-

ducting member with its end contacting the interior surface of the cup-shaped element, a conducting cup-shaped member surrounding the end of said outer tubular conducting member which is sealed to the cup-shaped element of insulating material and having its side walls spaced from the outer tubular conducting member and connected to said outer tubular conducting member, the open end of said coupling means communicating with the interior of the evacuated hollow conducting body, a second hollow conducting body having an aperture, the end of said coupling means provided with the cup-shaped element of insulating material extending within said second hollow conducting body through said aperture, the open end of said cup-shaped member having a flange securing said coupling means to said second hollow conducting member, and insulating means between the flange and said second hollow conducting member for permitting different direct voltages on said coupling means and said second hollow conducting member.

10. An evacuated hollow conducting body resonant at high frequencies, a coupling means for said body including a coaxial line having an outer tubular conducting member, a cup-shaped element of insulating material sealed to one end of the outer tubular conducting member and extending outwardly therefrom and an inner conductor coaxial with said outer tubular conducting member and extending outwardly past the end of said outer tubular conducting member with its end extending within the cup-shaped element, a conducting cup-shaped member surrounding the end of the outer tubular conducting member which is sealed to the cup-shaped element of insulating material and having its side walls spaced from the outer tubular conducting member and connected to said outer tubular conducting member at a point which is spaced from the sealed end thereof, the open end of said coupling means communicating with the interior of the evacuated hollow conducting body, and a second hollow conducting body having an aperture, the cup-shaped element extending within said aperture, said cup-shaped conducting member being secured to said second hollow conducting body.

11. A coupling means for an ultra high frequency evacuated device including a coaxial line having an outer tubular conducting member, a cup-shaped element of insulating material sealed to one end of the outer tubular conducting member and extending outwardly therefrom and an inner conductor coaxial with said outer tubular conducting member and extending outwardly past the end of said outer tubular conducting member with its end within the cup-shaped element, a conducting cup-shaped member sur-

rounding the end of said outer tubular conducting member which is sealed to the cup-shaped element of insulating material and having its side walls spaced from the outer tubular member and connected to said outer tubular conducting member, a hollow conducting member having an aperture therein, the end of the coaxial line supporting the cup-shaped element of insulating material extending within said aperture, a flange on said cup-shaped member fixed to said hollow conducting member, and an insulator between said flange and said hollow conducting member, said flange having a radial dimension equal to substantially a quarter wavelength of the operating frequency of the ultra high frequency evacuated device.

12. A coupling means for an ultra high frequency evacuated device including a coaxial line having an outer tubular conducting member, a cup-shaped element of insulating material sealed to one end of the outer tubular conducting member and extending outwardly therefrom and an inner conductor coaxial with said outer tubular conducting member and extending outwardly past the end of said outer tubular conducting member with its end within the cup-shaped element, a conducting cup-shaped member surrounding the end of said outer tubular conducting member which is sealed to the cup-shaped element of insulating material and having its side walls spaced from the outer tubular member a distance equal to a half wavelength of the operating frequency of the ultra high frequency evacuated device and connected to said outer tubular conducting member, a hollow conducting member having an aperture therein, the end of the coaxial line supporting the cup-shaped element of insulating material extending within said aperture, a flange on said cup-shaped member fixed to said hollow conducting member, and an insulator between said flange and said hollow conducting member, said flange having a radial dimension equal to substantially a quarter wavelength of the operating frequency of the ultra high frequency evacuated device.
